(57) **CLAIM**

The ornamental design for a camera assembly, as shown and described.

DESCRIPTION

FIG. 1 is a top perspective view of a camera assembly;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines shown in the figures depict portions of the camera assembly that forms no part of the claimed design.

1 Claim, 3 Drawing Sheets
